United States Patent Office.

WILLIAM R. GARDNER, OF LEONARDSVILLE, NEW YORK.

Letters Patent No. 105,191, dated July 12, 1870.

IMPROVEMENT IN PESSARIES.

The Schedule referred to in these Letters Patent and making part of the same

To all whom it may concern:

Be it known that I, WILLIAM R. GARDNER, of Leonardsville, in the county of Madison and State of New York, have invented a new and improved Mode of Constructing Pessaries; and I do hereby declare that the following is a full and exact description thereof, reference being had to the accompanying drawing and to the letters of reference marked thereon.

The nature of my invention consists in providing a pessary, having at its upper end a hinged curved lip attached to a stationary curved lip of similar form and construction, in such manner as to admit of the hinged or adjustable lip being compressed into small compass for insertion, the lower end of said pessary being of the ordinary curved-lever form.

To enable others skilled in the art to make and use my invention, I will proceed to describe its construction.

A, Figure 1, is a top view of the pessary, showing the form of the lever portion of the same; also, the top or outside of the adjustable lip B, as it appears when closed.

B, Figure 2, is a transverse side view of the pessary. B represents the hinged or curved lip, open, as when in use.

c, one of the pins or rivets upon which it turns when being compressed or relaxed.

D D are dotted lines, showing the position of the adjustable lip B when closed for insertion, said lip being composed of hard or vulcanized rubber.

C, Figure 3, is a top view of the stationary portion

of the pessary, showing the form of the lever when the adjustable lip is removed.

D, Figure 4, is a perspective view of the entire pessary, showing its general shape and position, with the curved lip open to its full capacity.

It is evident, from the construction of this form of pessary, that it is readily passed through the vulva, and, by a proper movement of the index-finger, is opened and adjusted to the posterior and anterior surfaces of the lips and neck of the uterus, firmly securing it in position by resting against the inner surface of the pubic bone.

The principal advantages of this pessary over any form heretofore constructed are, that, by its adjustable curved lip, combined with the stationary curved lip of similar form, it affords a complete and perfect support for the uterus, thus enabling me to effectually control the most difficult cases of antversion, and antiflection, retroversion, retroflexion, and prolapsus of the uterus.

What I claim as new, and desire to secure by Letters Patent, is—

Attaching the adjustable curved lip B to a stationary curved lip of similar form and construction, when combined and arranged in the manner and for the purpose substantially as herein described and set forth.

WILLIAM R. GARDNER.
